UNITED STATES PATENT OFFICE

SAMUEL B. KRAUT, OF SOUTH BEND, INDIANA, ASSIGNOR TO WESTINGHOUSE ELECTRIC & MANUFACTURING COMPANY, A CORPORATION OF PENNSYLVANIA

LAMP SOCKET

Application filed December 14, 1928. Serial No. 326,031.

My invention relates to lighting devices and has particular relation to a lamp receptacle for such devices.

An object of my invention is to provide 5 a lamp receptacle or extension socket adapted for extending the space between the receptacle and the light center.

Another object of my invention is to provide means for making a firm, positive contact 10 between the current-carrying parts of the lamp and the receptacle.

Another object of my invention is to provide means for short-circuiting the current-carrying parts of the receptacle by removal 15 of the lamp.

A still further object of my invention is to provide a receptacle having current-carrying parts of such size and construction as to carry heavy currents without heating.

20 Referring to the drawing in which like figures indicate like parts;

Figure 1 is a top plan view of the receptacle;

Fig. 2 is a view, in perspective, of the receptacle with certain parts broken away for 25 better illustration, the non-metallic portions being indicated by broken lines;

Fig. 3 is a side view, partially in elevation and partially in section, of the device taken 30 along line III—III of Fig. 1;

Fig. 4 is a view, in section, of the lamp-gripping device utilized in my structure; and

Fig. 5 is a view, in perspective, of the 35 spring utilized as a part of the lamp-gripping device.

In practicing my invention, I provide a receptacle or socket extension comprising a plug portion having a threaded, shell member and a center contact adapted to be inserted in an ordinary receptacle, and a socket portion having a threaded shell member and a resilient center contact member, adapted for the reception of a lamp base.

45 A tongued portion of the threaded shell member in the socket portion of the receptacle is adapted to grip the lamp base and the resilient center contact is adapted to be moved downwardly by the lamp base against 50 a spring, thus causing a positive electrical

connection between the current-carrying parts of the lamp base and receptacle. Two electrically-conducting wing members on the resilient center contact, normally provide a short circuit between the threaded shell member of the socket and the resilient center contact. Insertion of the lamp base breaks the short circuit.

Referring more particularly to Figs. 2 and 3, the receptacle comprises a socket base 9 which may be of any suitable material, such as porcelain, recessed in the upper or socket end 10 so as to provide a recess 11 in which may be mounted a threaded female shell member 12. A cylindrical center contact 13 is mounted on a plunger 14 which in turn passes through and is engaged by a washer 15. A flexible connector 16 is fastened to the under-side of the cylindrical contact member and is secured by means of a bolt 17 and nut 18 to a suitable connector 18. The connector 18 in turn is secured and makes electrical connection with a contact 19 by means of a bolt 20 which passes through the base of the receptacle.

The center contact member 19, together with a male threaded shell member 21, constitute the electrical conducting means for the plug portion 22 of the receptacle. The threaded shell members are secured to the receptacle by means of screws 23 which are adapted to pass through the base of the female shell member 12 and through the base of the receptacle to the male shell member 21 where they engage the ring 24 constituting a portion of the male shell member 21. In addition to furnishing a means for fastening the shell members in place on the receptacle, the screws 23 constitute an electrically-conducting path between the two shell members.

It is very desirable that the lamp base (not shown) be gripped in the threaded shell member of the socket, so that a firm contact may be secured between the current-carrying parts of the base and receptacle and so that the lamp will not be unscrewed from the socket by reason of vibration. In order to grip the lamp base, I have provided a tongue portion 31 of the shell member ar-

ranged in such a manner that the tongue may be urged inwardly toward the center of the socket to grip the lamp base when the lamp is in place in the receptacle. In order to provide means for urging the tongue member inwardly, I have provided a spring member 32 shown in Fig. 5 having a resilient tongue 33 disposed at an angle to the spring member such that when the spring member is located under the receptacle and engaged in place by bolts which pass through a suitable opening 30 in the spring member, the tongue 33 urges the tongue member 31 of the shell inwardly to grip the lamp base.

The cylindrical center contact 13 mounted on plunger 14 is provided with extending wing portions 34 which are adapted to make contact with the bottom portion of the female shell member 12 when the center contact and plunger are in the normal extended position. A shoulder portion 35 on the inside of the receptacle provides a means for supporting the washer 15 against the pressure of the spring 36 and causes the center contact members and wings 34 normally to be urged upwardly against the base of the shell member 12. When the lamp base is inserted in the lamp receptacle and screwed down, the center contact of the lamp base is driven against the contact 13, moving it downwardly, and the downward movement of the contact causes the wing members 34 to be disconnected from the shell 12. The current carrying parts of the receptacle are then open circuited and the lamp is energized. This feature is very necessary in order that the remaining lamps in a series lighting circuit may be kept energized.

The invention, as shown and described, is directed to an extension socket which may be utilized when a lamp having a short distance between the base and light center is to be utilized or for any other condition in which a lamp receptacle is to be used but may be modified for use as a regulation lamp socket.

It is apparent that a positive contact is made between the different current-carrying parts of the lamp and receptacle and that the current-carrying parts are so arranged that they will carry heavy currents without over-heating. The plunger and center contact are arranged to move vertically against the lamp base and the spring is located in the cooler part of the receptacle so that a firm pressure and consequently a good electrical connection is always maintained with the lamp base.

It is apparent that modifications of my device may be made by those skilled in the art. Such modifications may be made without departing from the spirit and scope of

my invention as set forth in the appended claims.

I claim as my invention:

1. In a lamp receptacle comprising an extension lamp socket and a resiliently mounted center contact member, means for short-circuiting the electrical circuits of the receptacle comprising wing members on the center contact member adapted to contact with the base of the socket only when the lamp is removed. 70 75

2. In a lamp receptacle comprising an extension shell member for engaging a lamp base and a resiliently mounted center contact member, means for short-circuiting the electrical circuits of the receptacle comprising wing members on the center contact member adapted to contact with the shell member when the lamp is removed and to be disconnected from the socket by depression 80 85 of the center contact and wing members by the insertion of the lamp.

3. In a lamp receptacle comprising a plug member having a lower screw-threaded shell and a center contact member and a socket member having a screw-threaded shell and a plunger center contact member, a series cut-out associated with the plunger, means for electrically connecting the respective shell portions comprising a plurality of bolts 90 95 threaded through the two shells and means for electrically connecting the center contact portions comprising a plunger and an electrically conducting connector extending through the base of the receptacle to engage the lower center contact member. 100

4. In a lamp receptacle provided, at one end, with a plug member having a screw-threaded shell and a socket member, at the opposite end, having a screw-threaded shell 105 electrically connected to said first mentioned shell, said plug being provided with a center contact member, said socket member being provided with a plunger having an upper center contact member for said socket 110 and said center contact members being permanently electrically connected to each other and a series cut-out associated with said plunger.

In testimony whereof, I have hereunto 115 subscribed my name this 7 day of December, 1928.

SAMUEL B. KRAUT.
